UNITED STATES PATENT OFFICE.

ROBERT P. RECKARDS, OF GREAT FALLS, MONTANA.

DESIGN FOR A BANK-CHECK.

59,283.

Specification for Design.

Patented Oct. 4, 1921.

Application filed April 19, 1919. Serial No. 291,420. Term of patent 14 years.

To all whom it may concern:

Be it known that I, ROBERT P. RECKARDS, a citizen of the United States, and a resident of Great Falls, in the county of Cascade and State of Montana, have invented a new, original, and ornamental Design for a Bank-Check, of which the following is a specification, reference being had to the accompanying drawing, forming part thereof.

The figure is a face view of a bank check.

I claim:

The ornamental design for a bank check, as shown.

ROBERT P. RECKARDS.

Witnesses:

P. A. FISHER,
C. L. McDANIEL.
